UNITED STATES PATENT OFFICE.

HERBERT H. STEELE, OF MARCELLUS, NEW YORK, ASSIGNOR TO THE MONARCH TYPEWRITER COMPANY, OF SYRACUSE, NEW YORK, A CORPORATION OF NEW YORK.

TYPE-WRITING MACHINE.

1,106,420.

Specification of Letters Patent. Patented Aug. 11, 1914.

Application filed July 22, 1912. Serial No. 710,903.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates to paper feeding and controlling mechanism for typewriting machines and its general object is to provide improved mechanism of the character stated.

More specifically, the object of my invention is to provide a device which may be readily applied to existing styles of typewriting machines and which is particularly adapted for duplicating items on sheets which overlie each other but are differentially line spaced. For example, in carrying out the embodiment of the invention herein illustrated the object in mind was to provide, first, for filling in the blank spaces of bank drafts supplied in continuous form; second, for duplicating the typewritten matter in the bank draft on an underlying record sheet, the duplicated matter being condensed; and, third, for duplicating the amount of the draft, where written in figures, in condensed form on a tally sheet, which also underlies the draft at one end and is arranged side by side with the record sheet aforesaid.

In seeking to obtain the aforesaid results, one of the more specific objects of the invention has been to provide a divided platen, the divisions or sections whereof are associated with improved line spacing mechanism that is adapted automatically to actuate one platen section at each line spacing operation and to operate the other platen section intermittently.

Another specific object is to provide for line spacing three separate work sheets preferably in continuous form, by primary line spacing mechanism in combination with secondary paper feeding devices for one of the work sheets, said devices being operative during a partial cycle of motion to feed this sheet a predetermined distance while the other sheets are quiescent, said devices operating independently of the primary line spacing devices.

Another specific object is to provide paper feeding mechanism that is operative first to release the pressure devices co-operative

with the platen and next to move the associate work sheet a predetermined distance, these results being accomplished by a single continuous operation of said paper feeding mechanism.

Another specific object is to provide paper feeding mechanism for a plurality of work sheets, the mechanism for one of said sheets being actuated by a rotative hand piece and operating during one cycle of movement to release the paper pressure devices co-operative with the platen and the other work sheets, next to feed the first mentioned work sheet a predetermined distance and then to restore the paper pressure devices to operative position.

Other specific objects will hereinafter appear.

To the above ends my invention consists in the features of construction, combinations of devices and arrangements of parts herein-after described and particularly pointed out in the claims.

In the accompanying drawings, Figure 1 is a fragmentary front elevation of the platen carrier or carriage of a Monarch typewriting machine embodying my invention. Fig. 2 is a side elevation partly in section of said carriage and its mounting. Fig. 3 is a sectional view taken on a plane indicated by the dotted line $x-x$ in Fig. 1 and looking in the direction of the arrows at said line. Fig. 4 is a perspective view of a part hereinafter referred to as a pressure roll supporting bracket. Fig. 5 is a perspective view illustrating the courses taken by the various work sheets as they are fed through the machine. Fig. 6 is a diagrammatic side view of some of the paper feeding devices in abnormal position. Fig. 7 illustrates some of the parts of Fig. 6 in different relationships. Fig. 8 is a longitudinal sectional view of the divided or sectional platen. Fig. 9 is a fragmentary face view of the bank draft sheet or main work sheet and also of the underlying record sheet and the tally strip.

As appears from Figs. 1 and 2, the top plate 1 of the Monarch machine has secured to it brackets 2 which support grooved guide ways 3 and 4, the latter co-operating through anti-friction rollers 5 with the grooved rear bar 6 of a platen frame, carrier or carriage which further comprises end bars 7 in which is journaled the axle or shaft 8 of the platen.

110

The platen in the present instance, as best appears from Fig. 8, is a divided one, made up of two sections, of which the main or left-hand section 9 comprises a wooden core 10 and a rubber sheath 11. Secured to the left-hand end of the platen section 9 is a head 12 provided with crown ratchet teeth 13 and having also a hub 14 which receives a set screw 15 that coöperates with the shaft 8, said set screw thus securing the platen 9 in rigid relationship with the shaft 8. As appears from Fig. 1 the series of teeth on the ratchet 13 cooperates with a line spacing pawl 16 of the usual description that is controlled by a lever 17 shaped to provide the usual finger piece or key. The usual detent (not shown) for the ratchet 13 is also provided. From Fig. 8, it will be seen that a platen head 18 is secured to the right-hand end of the platen or section 9 by wood screws 19, the outer face of said head being flush with the end of the sheath 11 and partly underlying said sheath. The head 18 is provided with an elongated hub 20 which rounds and is supported by the axle 8. The hub 20 provides a bearing or support for a right-hand or a second platen section 21 which comprises a wooden core 22 and a rubber sheath 23. Secured to the left-hand end of the core is a head 24 which underlies the sheath 23 and abuts against the outer face of the head 18. Secured by wood screws 25 to the right end of the core 22 is a platen head 26 provided with a series of peripheral ratchet teeth 27. Abutting the outer face of the head 26 is a ratchet wheel 28 having peripheral teeth 29 equal in number to the teeth 27. The wheel 28 is of somewhat larger diameter than the head 26 so that the roots of the teeth 27 and 29 terminate at different distances from the axis of rotation, that is, the axle 8. At least this is true of the greater number of the teeth 29; but every third notch 29^a between said teeth is cut to a greater depth than its fellows so that it terminates at the same distance from the axis of rotation as do the notches between the teeth 27. The ratchet wheel 28 is provided with a hub 29^b which bears on the outer end portion of the hub or sleeve 20 and abuts against the right-hand end bar 7. A cross pin 30 passes through the hub 29^b, hub 20 and axle 8 and secures these parts together. The construction is such that both of the heads of the platen 9 are fixed to the shaft 8 as are also the ratchets 13 and 29; while the platen section 21 and its ratchet 27 are normally loose on the shaft 8 and may turn relatively thereto. It will be understood that the actuation of the line spacing lever 17 operates to turn or line space the platen section 9 but never to actuate the section 21.

Line spacing devices of novel construction are provided for turning or line spacing the

platen section 9 at each actuation and for intermittently or at every third actuation turning or line spacing the platen section 21. Said novel devices are best shown in Figs. 1, 3 and 8 and comprise a lever or arm 31 provided with a hub 32 which bears loosely on the hub 29^b and is confined between the ratchet wheel 28 and the end bars 7. The free end of the arm 31 terminates in a finger piece or key 33 and diametrically opposite thereto is a lug or projection 34 which carries a pin 34^a over which is hooked a draw spring 35, the rear end of which is anchored to a pin 36 on the carriage. The spring normally maintains the lug 34 in engagement with a stop pin 37 projecting laterally inward from the right-hand end bar 7. The arm 31 serves as a pawl carrier, having pivoted to it at 38 a pawl member 39 which depends from the pivot 38 and terminates at its lower end in a pawl tooth 40 which is extended leftward so that it is adapted to coöperate with the ratchet 27 as well as with the ratchet 29. The pawl 40 operates as a gravity pawl and is prevented from being swung too far out of operative position by a stop pin 41 on the arm 31, said stop pin coöperating with the tail portion 42 of the member 39. The frame rod or bar 43 which is secured to the end bars and is or may be of the usual paper finger rod, provides a back stop for the arm 31 and so limits the swinging movement thereof that the pawl 40 coöperates with its ratchets to turn their respective platens only a single unit's line space distance at each actuation. A roller detent 44 mounted on a spring arm 45 which is secured to the rod 43 coöperates with the ratchet 27 to maintain it and the platen section 21 in adjusted positions. The construction is such that when the pawl 40 coöperates with the notches of ordinary depth in the ratchet 29 it will be held out of engagement with the ratchet 27 because of the smaller diameter of the latter. This will be plain from Fig. 3. Consequently with the parts so related an actuation of the finger piece or key 33 will cause the pawl 40 to coöperate only with the ratchet 29 and it will turn or line space the platen section 9 without affecting the platen section 21. At every third actuation of the key 33, however, one of the deeper notches 29^a will be brought opposite the pawl tooth 40 and will permit said pawl tooth to swing in far enough to engage not only with the ratchet 29 but also with the ratchet 27. Consequently if now the key 33 be actuated it will operate to turn both the platen sections 9 and 21, said sections turning simultaneously and the effect being the same as if the platen were a single unitary platen instead of a divided platen. It will be seen that I have provided line spacing devices which operate constantly

to advance one platen or platen section and intermittently to advance another platen or platen section, the intermittent operation being periodic and in the present instance occurring at every third actuation of the line spacing devices.

5 Coöperative with the left-hand platen section 9 are feed rollers 46 and 47 of the usual description, said feed rollers being respectively mounted on pairs of spring pressed arms 48 and 49. The feed rollers 46 and 47 are releasable by devices comprising a rock shaft 50 provided with projections 51 that coöperate with pins or lugs 52 on the arms 48. The rock shaft 50 is controlled for releasing purposes by a crank arm 53 secured to its left-hand end and connected with a toggle element 54 provided with a finger piece or key 55 and pivotally connected at 56 with a second toggle element 57 pivoted to the platen frame (Fig. 2). By pulling forward the key 55 the shaft 50 is rocked and the rollers 46 and 47 are released or moved away from the platen and held in released position as is well understood, this construction being common to the Monarch machine.

The work sheets in the present instance are supported on a frame or carrier (Figs. 1 30 and 2) comprising end plates 58 and a cross rod 59, the ends of which are threaded and coöperate with pairs of nuts 60 associated with the end plates, one nut of each pair at the outer face and the other at the inner face of each end plate. The construction provides for readily adjusting the relationship between the plates. Near their lower ends the end plates are provided with hubs 61 which fit over the frame rod 43 and are 35 suitably secured thereto as by pins 62. These pins may be readily removed with a punch or other tool and then the rod 43 may be detached from the platen frame. The 40 construction enables the supporting frame comprising the end plates 58 to be readily mounted on the platen frame and also to be detached therefrom. To give the supporting frame additional stability the end plates 58 terminate at the rear in ears 58^a which 45 are notched as indicated at 63 to fit over the rock shaft 50. At the rear of the plates 58 is suitably secured a cross plate or bar 64. Said bar 64 provides a support for a box or container 65 which is preferably made of a 50 single piece of sheet metal and is secured to the rod 64 as by rivets 66. The box 65 comprises a bottom, a rear or back portion and opposite side portions, these being preferably punched out as shown, to promote 55 lightness. The side portions terminate at their rear upper corners in ears 67 perforated as indicated at 68 to receive lugs or projections 69 extending laterally from a top plate 70, said top plate being bent at the 60 front to provide a finger piece 71 and a

downward projection 72 at the front of the box. The top plate 70 is thus pivotally supported on the box and may be readily swung up to give access to the interior thereof. A flat spring 73 secured at the rear of the box 70 coöperates with the rear edge of the top 70 to maintain it down in normal position and also to hold it up when it has been swung back. The upper part of the bar 64 projects above the bed or bottom of the box 75 across its front and provides an abutment corresponding with the projection 72 at the top. It will be understood that the front of the box is open for the greater part but that closures or abutments 64 and 72 are provided near the top and bottom of the opening. The box 65 provides a receptacle for the main work sheet 74 which in the present instance is in a continuous form, being composed of a series of bank drafts printed in 80 blank as illustrated in Fig. 9, each blank at the top and bottom being joined to its neighbors by a fold, the blanks folding together somewhat like a fan. The arrangement is clearly shown in Fig. 5 and it is such that a 85 pack of blanks is provided, the blanks, however, instead of being separate as is ordinary, each being connected at one long edge with the blank in front of it and at the other long edge with the blank behind it. 90 By lifting the cover plate 70 such a pack may readily be arranged within the box or holder 65. The partial closures 64 and 72 prevent the pack from being forced by its own elasticity out of the front of the box or 95 from working out of the same accidentally, but the opening between these closures is quite wide and readily permits the continuous folded blank to be pulled out as needed, 100 section by section. The free end portion of the sheet 74 is drawn down behind the platen and between it and the feed rollers 46 and 47. The work sheet 74 extends substantially through the full width of the two 105 platen sections and passes up at the front of the machine behind a guide rod 75. Said 110 guide rod extends lengthwise of the platen in front of the same and is secured at its ends to the plates 58. After passing the printing line the work sheet 74 is controlled 115 by paper feeding devices comprising a rubber faced roller 76, the reduced ends 77 whereof taking bearings in the plates 58. Coöperative with the roller 76 is a somewhat larger rubber faced roller 78 which is 120 fixed to a shaft 79 that also takes bearings in the plates 58. The roller 78 is cut away and reduced in diameter as indicated at 80 so that for only part of its circumference can it coöperate with the roller 76. The 125 shaft 79 projects outward beyond the right-hand plate 58 and receives a cam member 81, said cam member, as shown in Fig. 1, having a hub 82 which receives a set screw 83 by which the cam member is secured to 130

said shaft 79. Outside the cam member is arranged a crank arm 84 having a hub 85 secured to the shaft 79 by a set screw 86. The crank arm 84 is provided with a finger piece or key 87. The periphery of the cam member 81 co-operates with a nose 88 on the forward arm of a lever 89 fulcrumed on a pivot screw 90 secured to the outer face of the right-hand plate 58. The opposite arm of said lever co-acts with an arm 91 secured to the rock shaft 50. The periphery of the cam member 81 is concentric except where it is notched out as indicated at 81^a, and normally the nose 88 is seated in the notch as shown in Fig. 2. At this time the reduced portion 80 of the roller 78 is opposite the roller 76 so that said rollers are not in active co-operation and the work sheet 74 passes loosely upward between them. If, however, the key 87 be pulled forward in the direction of the arrow in Fig. 2 to the position shown in Fig. 6, the nose 88 will be forced up on the high part of the periphery of the cam member, thus turning the lever 89 on its fulcrum and causing the lower arm thereof, acting against the crank arm 91, to rock the shaft 50 and effect the release of the feed rollers 46 and 47, the shaft 50 however not being rocked far enough to lock the toggle 54, 57. At the same time the working face of the roller 78 will be brought into co-operation with the roller 76 so that if now the rotation of the key 87 be continued the feed rollers 76 and 78 will co-operate to advance the work sheet 74 around the platen which, of course, will remain motionless. The advance of the work sheet will continue until the parts reach the position illustrated in Fig. 7, thus nearly completing a full revolution of the key 87. If the key be advanced to move the parts from the Fig. 7 position back to the normal position in Fig. 2, the working face of the roller 78 will separate from the roller 76 and the nose 88 will re-enter the notch 81^a, permitting the lever 89 to swing back to normal position and allowing the feed rollers to return to co-operation with the platen. It will be understood that ordinarily a turning movement of the platen will operate through these pressure devices or feed rollers 46 and 47 to advance the work sheet 74 in line spacing direction; and it will further be understood that by manipulating the key 87 the feed rollers may be thrown off and the work sheet may be advanced independently of the platen by the independent devices or rollers 76 and 78. The work sheet 74 receives impressions directly from the main ribbon which is acted on by the types at the front of the platen.

In order to transfer the type impressions from the work sheet 74 to underlying sheets, a transfer medium is provided, said transfer medium being in the form of a continuous sheet of very thin carbon paper 92 which is

rolled up on the usual paste-board core, said core being frictionally secured on a supporting roller 93 which may be of metal tubing provided with end or axial portions 94, these portions being seated in inclined slot-ways 95 formed in the upper ends of the plates 58. The carbon paper 92 is wound on the supporting roller with the carbon face outside and is led off rearward from the under side of said roller over a guide rod 96 on the supporting frame, and thence downward behind the platen and around it and up at the front side where it is wound on a receiving roller 97 having end portions 98 seated in the guide slots 95. The receiving roller is supported on the delivery roller and through the force of gravity the turning movements of the delivery roller are transmitted to the receiving roller and cause the used carbon to wind automatically thereon. The carbon paper 92 is substantially the width of the work sheet 74 and passes around the platen between it and said work sheet 74 with the carbon face inward toward the platen.

The supporting frame comprising the plates 58 provides also a support for the record sheet and the tally strip heretofore referred to, an additional or intermediate plate 99 being also provided for this purpose. Said plate 99, as shown in Fig. 1 is supported at its upper end on the rod 59, being clamped to said rod by nuts 100 which co-operate with threaded portions of the rod at opposite sides of the plate 99 and grip said plate between them. The lower end of the plate 99 is provided with a hub 101 which may be pinned as indicated at 102 to the frame rod 43. The end plates 58 and the intermediate plate 99 are provided with slots 103 which are open at the top and extend downward, inclining slightly rearward, the slots registering, of course, with each other. The slot 103 in the left-hand plate 58 and that in the intermediate plate 99 receive the end portions 104 of a supporting roller 105 for the record sheet 106. Said record sheet passes downward from its support and around the left-hand platen section 9 only, passing between said platen section and the co-operating feed rollers and underlying the carbon sheet 92. The record sheet 106 is wound on a receiving roller 107, the end portions 107^a whereof co-operate respectively with the slot 103 in the left-hand plate 58 and with the slot in the intermediate plate 99. The receiving roll 107 rests on the periphery of the rolled up portion of the sheet 106 on the supporting roll 105 and is automatically actuated thereby so that as the record sheet is unwound from the delivery roll it is wound on the receiving roll.

The tally strip 108 is wound on a supporting roller 109 having end portions 110 and 111 which engage respectively with the slots 103 in the plate 99 and in the right-hand

plate 58, the tally roll being arranged between these last mentioned plates and in register with the right-hand platen section 21 over which it is adapted to be fed. The tally is drawn downward at the front of its delivery roll 109 and over a feed roller 112 which co-operates with the top of the platen, being supported on a Y-shaped bracket 113 best illustrated in Fig. 4. Said bracket is preferably of spring metal and is secured to the top of the rod 43 by a headed screw 114 (Fig. 2). The tail of the bracket 113 engages with a pin 115 on the supporting frame. The construction is such that by screwing in or out on the screw 114 the pressure of the feed roller 112 may be varied. The tally strip is drawn around the front of said feed roll and between it and the platen section 21 passing around said platen section beneath the right-hand portion of the carbon sheet 92 and upward at the front of the platen to a receiving roll 116, the ends 117 and 118 whereof bear in the guide slots 103 above the delivery roll 109. The receiving roll 116 rests on the delivery roll and is automatically actuated thereby to wind up the used portion of the tally strip.

In making use of the invention for the printing of bank drafts and appropriate records, the three work sheets 74, 106 and 108 are arranged so that the sheets 106 and 108 are side by side and underlie the sheet 74 while the carbon sheet 92 is interposed between them. The sheet 74 is positioned so that the date line on the first blank is opposite the printing point; while as shown in Fig. 3 the pawl tooth 40 is opposite one of the shallow notches in the ratchet wheel 28 immediately below one of the deep notches 29a. The operator first fills in the date on the draft, this being duplicated through the carbon sheet 92 on the underlying record sheet 106. The key or finger piece 33 is then actuated, line spacing the platen section 9 and advancing the sheets 74, 92 and 106 a unit's distance, the tally strip of course remaining stationary. The feed rolls 46 and 47 are then released by operating the key 55 and the sheet 74 is drawn upward or advanced by hand independently of the other sheets until the line "Pay to the order of" is opposite the printing point. The feed rollers are then restored and the name is filled in, being simultaneously transferred through the carbon sheet to the record sheet 106; also the amount of the draft in figures is filled in after the dollar sign, transferring through the carbon sheet 92 simultaneously on to the tally strip 108. The platen 9 is again line spaced by actuating the key 33, thus advancing the sheets 74 and 106 another unit of line space distance and the amount of the draft in words is printed on the sheet 74 and simultaneously transferred to the sheet 106. Thereupon the key 33 is

again operated, but this time the pawl 40 will engage with a deep notch 29a and will operate to turn both the platen sections, advancing all the work sheets simultaneously. This completes the filling in of the first blank draft which is then ready for the signature of the bank official. The operator next turns the key 87 forward through a complete cycle of rotation, this operation first releasing the feed rollers and then advancing the main work sheet 74 continuously and independently of the platen a distance such that the date line on the next succeeding blank form is brought opposite the printing line. Preferably the drafts are perforated on their folded edges as indicated at 74a so as to facilitate their separation from the continuous sheet or strip. As will be understood from what has been said and as appears from Fig. 9 the operations above outlined result in the filling in of the blanks on the draft, the duplication of this matter in condensed form on the underlying work sheet 106 and the printing of the draft totals in condensed form on the tally strip 108. In Fig. 9, the record sheet and tally strip are shown advanced far enough to expose the printing.

By the use of my invention as described, the preparation of bank drafts is greatly facilitated; as heretofore it has been necessary to employ blanks in book form with stub ends, and each draft has required the filling in of the blank drafts, the separate filling in of the stubs with a pen, and the preparation of a separate slip for the book-keeper.

Although the present form of my invention is designated for use in the preparation of bank drafts, it is to be understood, of course, that said invention may be used for various other styles of commercial typewriting for which it may be adopted; also that changes of form may be made without departing from my invention and parts of it may be used without other parts.

What I claim as new and desire to secure by Letters Patent, is:—

1. In a typewriting machine, the combination of a platen comprising a plurality of sections, line spacing ratchet wheels for each section, a single hand controlled pawl co-operative therewith, and means for affording differential feeding movements of said platen sections.

2. In a typewriting machine, the combination of a platen comprising a plurality of sections constantly free to be rotated independently of each other, and differential line spacing mechanism for advancing said sections differentially, said mechanism comprising a single hand-actuated pawl.

3. In a typewriting machine, the combination of a platen comprising a plurality of sections constantly free to be rotated in-

- dependently of each other, line spacing mechanism comprising a single pawl, and means for affording an advance of one platen section each time said pawl is actuated and for affording an intermittent advance of another platen section.
4. In a typewriting machine, the combination of a platen comprising a plurality of independent co-axial sections, line spacing ratchet wheels one for each section and arranged side by side, a hand controlled pawl having a tooth co-operative with both of said ratchet wheels, and means for affording differential action of said pawl on said ratchet wheels.
5. In a typewriting machine, the combination of a platen comprising a plurality of independent co-axial sections, line spacing ratchet wheels one for each section and arranged side by side, and a hand controlled pawl having a tooth co-operative with both of said ratchet wheels, said pawl co-operating with one of said ratchet wheels at each actuation but co-operating only intermittently with the other ratchet wheel.
6. In a typewriting machine, the combination of a platen comprising a plurality of independent co-axial sections, line spacing ratchet wheels one for each section and arranged side by side, a hand controlled pawl having a tooth co-operative with both of said ratchet wheels, and means for affording differential action of said pawl on said ratchet wheels, said pawl co-operating at each actuation with one of said ratchet wheels and at every third actuation only with the other ratchet wheel.
7. In a typewriting machine, the combination of a platen comprising a plurality of independent co-axial sections, line spacing ratchet wheels one for each section and arranged side by side, and a hand controlled pawl having a tooth co-operative with both of said ratchet wheels, one of said ratchet wheels being of a greater diameter than the other and being constructed to permit intermittent co-operation of said pawl with the smaller ratchet wheel.
8. In a typewriting machine, the combination of a platen comprising a plurality of independent co-axial sections, line spacing ratchet wheels one for each section and arranged side by side, a hand controlled pawl having a tooth co-operative with both of said ratchet wheels, one of said ratchet wheels being of a greater diameter than the other and certain of its teeth being notched out to greater depth than the others to permit co-operation of said pawl with the smaller ratchet wheel.
9. In a typewriting machine, the combination of a platen comprising a plurality of independent co-axial sections, line spacing ratchet wheels one for each section and arranged side by side, a manually controlled
- arm pivoted co-axially with said sections, and a pawl mounted on said arm and co-operative with both of said ratchet wheels.
10. In a typewriting machine, the combination of a platen comprising a plurality of independent co-axial sections, line spacing ratchet wheels one for each section and arranged side by side, a manually controlled arm pivoted co-axially with said sections, and a gravity pawl pivoted to said arm and provided with a tooth that overlies and is adapted to co-operate with both of said ratchet wheels.
11. In a typewriting machine, the combination of a platen comprising a plurality of sections constantly free to be rotated independently of each other, line spacing devices for actuating one only of said sections and other line spacing devices operative on both said sections and adapted to differentially actuate the same.
12. In a typewriting machine, the combination of a platen, two feed rollers co-operative with each other independently of the platen, and means brought into use automatically for affording co-operation of said rollers during a part of a revolution only thereof, said rollers separating and remaining separated during the remaining part of the revolution.
13. In a typewriting machine, the combination of a platen, and two feed rollers co-operative with each other independently of the platen, one of said feed rollers being cut away so that it co-operates with the other during part only of a revolution.
14. In a typewriting machine, the combination of a platen, a feeding device co-operative therewith to feed a work sheet, independent feeding means for feeding the same work sheet, and means operative first to throw said feeding device out of co-operation with the platen thereby releasing said work sheet, and for thereafter actuating said independent means to advance said work sheet.
15. In a typewriting machine, the combination of a platen, a pressure device co-operative therewith to maintain a work sheet in co-operation with the platen, paper feeding means for feeding the same work sheet independently of the platen, and means for rendering said pressure device inoperative to hold said work sheet and for thereafter actuating said paper feeding means.
16. In a typewriting machine, the combination of a carriage, a platen, a pressure device co-operating therewith to maintain a work sheet in co-operation with the platen, a pair of co-operative feed rollers for advancing the same work sheet independently of the platen, manual means for actuating said feed rollers, and operative connections between said manual means and said pressure device.

17. In a typewriting machine, the combination of a platen, a pressure device coöperative therewith to maintain a work sheet in coöperation with the platen, independent feed rollers operative to advance said work sheet independently of the platen, and means for rendering said pressure device inoperative during coöperative movements of said feed rollers, said feed rollers being cut away so that they are effective during a part only of each revolution.
18. In a typewriting machine, the combination of a platen, a feed roller coöperative therewith to maintain a work sheet thereagainst and to feed the same over the platen, a pair of feed rollers operative independently of the platen to advance said work sheet, and means operative to release said first named feed roller and for thereafter effectively operating said independent feed rollers.
19. In a typewriting machine, the combination of a platen, a main feed roller coöperative therewith, two feed rollers coöperative independently of the platen, and manual means operative first to release said main feed roller and second to actuate said two feed rollers.
20. In a typewriting machine, the combination of a platen, a main feed roller coöperative therewith, two feed rollers coöperative independently of the platen, and manual means operative first to release said main feed roller, second to actuate said two feed rollers and finally to render said two feed rollers inoperative and to afford a return of said main feed roller to operative engagement with the platen.
21. In a typewriting machine, the combination of a platen, a main feed roller, coöperative with the platen to advance a work sheet thereover, releasing means therefor comprising a rock shaft, two independent coöperative feed rollers for feeding the same work sheet independently of the platen, and means including a key for actuating said independent feed rollers and for rocking said shaft, said shaft operating to release said feed roller and said work sheet prior to the effective operation of said independent feed rollers to advance said work sheet.
22. In a typewriting machine, the combination of a platen; a main feed roller operative with the platen to advance a work sheet thereover; releasing means therefor comprising a rock shaft; two independent coöperative feed rollers for feeding the same work sheet independently of the platen; and means for actuating said independent feed
- rollers and for rocking said shaft, said means including a key, a cam operative by said key and a lever operative by said cam and adapted to rock said shaft, said shaft operating to release said feed roller and said work sheet prior to the effective operation of said independent feed rollers to advance said work sheet.
23. In a typewriting machine, the combination of a platen, a main feed roller, releasing means therefor comprising a rock shaft, two independent coöperative feed rollers, and means including a key for actuating said independent feed rollers and for rocking said shaft, said key being rotatable through a complete cycle of rotation and said independent feed rollers being cut away so that they coöperate during part only of said cycle.
24. In a typewriting machine, the combination of a platen, a main feed roller, releasing means therefor comprising a rock shaft, two coöperating independent feed rollers, and means for actuating said independent feed rollers and for rocking said shaft, said means including a key rotatable through a complete cycle of rotation and said independent feed rollers being cut away so that they coöperate during part only of said cycle, said means also including a cam controlled by said key and operative on a lever which rocks said shaft.
25. In a typewriting machine, the combination of a platen, a pressure device coöperative therewith to feed a work sheet, means for releasing said pressure device, and means for concurrently feeding said work sheet independently of the platen.
26. In a typewriting machine, the combination of a platen, a pressure device coöperative therewith to feed a work sheet, means for releasing said pressure device, and means for concurrently feeding the same work sheet independently of the platen, both said means being controlled by a single key.
27. In a typewriting machine, the combination of a platen frame, a platen thereon, a pressure roll, a single V-shaped spring arm carrying said pressure roll, and a screw securing said holder to said platen frame and adjustable to vary the pressure of said roll.

Signed at Syracuse, in the county of Onondaga, and State of New York, this 18th day of July A. D. 1912.

HERBERT H. STEELE.
